US00D848555S

(12) United States Design Patent (10) Patent No.: US D848,555 S
(45) Date of Patent: * May 14, 2019

(54) YOGA ROLLER

(71) Applicant: Hui-Chin Chang, Taichung (TW)

(72) Inventor: Hui-Chin Chang, Taichung (TW)

(73) Assignee: Hermes Clues Industries Co. Ltd.,
Taichung (TW)

() Term: 15 Years

(21) Appl. No.: 29/611,663

(22) Filed: Jul. 24, 2017

(51) LOC (11) Cl. 21-02

(52) U.S. Cl.

USPC D21/688
